UNITED STATES PATENT OFFICE.

WILLIAM J. SCHAEFER, OF ONTARIO, CALIFORNIA.

COOKER.

1,197,154.

Specification of Letters Patent. Patented Sept. 5, 1916.

Application filed December 28, 1914. Serial No. 879,257.

To all whom it may concern:

Be it known that I, WILLIAM J. SCHAEFER, a citizen of the United States, residing at Ontario, in the county of San Bernardino and State of California, have invented a new and useful Cooker, of which the following is a specification.

This invention relates to apparatus for cooking fruit, vegetables, meat, fish, etc., contained in cans, while such cans are in transit through the apparatus, so as to provide for continuous receiving, cooking and delivering operation on a line of cans, and the main object of the invention is to enable the heat to be delivered to the cans in the most effective manner, whereby maximum cooking temperature is obtained in the cans without the use of unduly superheated steam. In cooking canned goods, particularly such as require a relatively high temperature for effective cooking, it is a matter of great difficulty to get the required amount of heat into the interior of the cans, without unduly lengthening the time required for cooking and correspondingly increasing the size and cost of the apparatus, or without using steam superheated to such a high temperature as to make the operation impracticable on account of the expense and other objections. This difficulty I overcome by transmitting the heat, or a portion thereof, to the interior of the can, by conduction from a heated body or support on which the can travels, the can being in conductive contact with such support, so as to greatly increase the rapidity with which the heat will pass from the heating pipe or source of heat, to the can, as compared with the usual methods of transmission by convection and radiation.

The accompanying drawings illustrate embodiments of my invention, and referring thereto:

Figure 1 is a side elevation of the cooker, partly in section. Fig. 2 is an end elevation thereof, partly in section. Fig. 3 is a plan view of a portion of the track means and the heating means therefor. Fig. 4 is a detail section of one of the screw conveyer and track means, and the heating means associated therewith. Fig. 5 is a section of another form of the track and heating means. Fig. 6 is a section of a form of the invention in which the heating pipe is used

as the track means. Fig. 7 is an end elevation of the apparatus, with the casing removed, to show the transfer mechanism. Fig. 8 is a partial longitudinal section, showing the transfer means.

My invention is illustrated in connection with the form of cooker disclosed in my Patent No. 1,044,822, dated Nov. 19, 1912, but it will be understood that it is applicable in connection with any form of continuous cooker, wherein the cans are caused to move continuously along a supporting track.

1 indicates the casing of the apparatus, in which are mounted a series of conveyers comprising substantially horizontal shafts 2, arranged in pairs, the shafts of each pair being provided with oppositely winding screw flanges 3 and extending on opposite sides of a track means 4. Bearings 8 are provided to engage and support the screw conveyers at intervals along the same. Said track means 4 is shown in Fig. 1 as consisting of a flat rail, supported on the bearings 8. Below each track means is provided a heating pipe 5, which is in conductive contact with said track, and is preferably embedded or set into the track rail so as to be in effective heat conductive relation therewith. For this purpose the rail 4 may be formed with a channel 4' in its lower face, partially embracing or fitting on the heating pipe 5. The several pipes 5 are connected at opposite ends thereof respectively to headers 6 and 7, which are connected respectively to a steam supply header 6' and to an outlet header 7' for carrying away or 80 circulating the heating medium.

The screw conveyer shafts 2 are driven by any suitable means, for example by bevel gears 9 thereon, meshing with bevel gears 10 on shafts 11, driven by gearing 12 and 13 95 from a driving shaft 14. In order to provide sufficient heating capacity, the heating and conveying units consisting of the above described tracks and screw conveyers are preferably arranged in stacks or vertical sets, and means are provided for transferring the cans from each conveyer to the next conveyer of the set, said means consisting, for example, of star wheels 16 working within guides 17 whereby the cans 105 are received from the delivery end of each conveyer and lifted to the next higher conveyer.

Means are also shown for transferring the cans from the final conveyer of the first set, to the first conveyer of the next set. For this purpose there is provided, preferably at one end of the apparatus, a guide or way formed for example of rails 18 and 19 mounted on yokes 20, and screw conveyers 21 mounted adjacent to said rails, so as to engage the cans as they are delivered to such way, and carry them along the way. This guideway extends obliquely or diagonally from the delivery end of the top conveyer of one set, to the receiving end of the bottom conveyer of the next set. The shafts 21 of screw conveyers 21 are driven from the gearing connections 13 through gearing 25, and the star wheels 16 may also be driven from the same gearing connections through gearing 26. The casing 1 is provided with an inlet 22 through which the cans are fed to the first conveyer of the first set, and with an outlet 23 through which the cans are discharged from the last conveyer of the last set. A chute 34 and feed wheel 35 may be provided at the inlet.

Additional heating means may be provided, comprising pipes 24 extending parallel to the tracks 4, so as to heat the cans by radiation and convection, while the track pipes 5 are heating the cans by conduction. These pipes 24 may be connected to the headers 6 and 7 aforesaid. If further heating is required, a steam supply pipe 28 may be provided at the lower part of casing 1, having perforations 28' for supply of steam into the interior of casing 1; and in order to superheat such steam, a steam heater may be provided, consisting of pipes 30 extending over the steam supply pipe or pipes 28 and connected at their ends to inlet and outlet headers 31 and 32.

The operation of the cooker is as follows: The cans are fed in through the inlet 22 and are moved along the track 4 of the lowermost conveyer of the first set by the action of the screw conveyer members 3, and are then transferred to the next higher conveyer by the star wheel 16 at the delivery end of the first conveyer. The second conveyer moves the cans back along the next track above, and the operation proceeds in this manner until the cans reach the delivery end of the highest conveyer of the first set, whence they are transferred, by operation of screw conveyers 21, to the lowermost conveyer of the second set, and are then fed through the second set in similar manner and discharged at outlet 23. In passing along the series of track rails 4, the cans are heated by conduction of heat, through the metal of the rails, directly from heating pipes 5, to the cans, the other pipes 24 aiding the operation of heating means 5 by applying heat by radiation and conduction, to all parts of the cans; and the steam arises

ing from the steam supply pipe 28 and heated by the pipes 30, further aiding in the heating operation. I have found that by the use of direct conduction in the manner above described, I am enabled to apply or transmit the heat so efficiently to the contents of the cans, that with a given steam temperature, it is possible to make the heating apparatus considerably smaller, or in case it is desirable, to increase considerably the actual cooking temperature on the goods in the cans. This enables the goods to be cooked more quickly, which is of great advantage, particularly in cooking fruit, as it preserves the flavor of the fruit better.

The form of track shown in Fig. 1 is particularly adapted to shallow cans, such as fish cans. In case high cans, such as fruit cans, are to be heated, the track rail may be made as a T rail as shown at 37 in Fig. 5, and the heating pipes 5' may be mounted in the angles of the T's, so as to be in contact with the rails. Or, as shown in Fig. 6, the heating pipe may itself be used as the track. I prefer, however, to provide a flat track for the can to roll on, as it gives a better conductive contact for the can with the track.

What I claim is:

1. A cooker comprising a casing, track means extending therein and adapted to support a line of cans, means for moving the cans along said track means, heating pipes extending into said casing and adjacent to said track means in conductive relation thereto, and means for supplying heating medium to the interior of the casing, in contact with the cans therein.

2. A cooker comprising a casing, track means extending therein and adapted to support a line of cans, means for moving the cans along said track means, heating pipes extending below and in contact with said track means for heating the cans by conduction, heating pipes extending within the casing and over the track means to heat the cans by radiation and means for supplying heating medium to the interior of the casing, in contact with the cans therein.

3. A cooker comprising a casing adapted to contain a heating medium, means for supplying heating medium thereto, a plurality of superposed tracks in said casing, means for conveying a line of cans successively along said tracks, heating pipes extending under and in contact with the respective tracks, to heat the cans on such tracks, by conduction, and to heat the cans on tracks below the same, by radiation.

4. A cooker comprising a casing, track means extending within said casing, means for conveying a line of cans along said track means, means for supplying heating medium to said casing to heat the cans therein by contact of said heating medium with said cans, and pipes extending in con-

ductive relation to said track means to heat the cans by conduction through said track means.

5. A cooker comprising a casing, means for supplying steam to the lower part thereof, heating pipes extending above said steam supply means to superheat the steam rising therefrom, can conveying means extending over the aforesaid pipes, pipes extending adjacent to the respective can conveying means and adapted to apply heat to the cans by conduction.

6. A cooker comprising a casing, means for conveying cans therethrough, means for supplying steam to said casing, means for superheating said steam while in the casing, and means extending adjacent to the cans on the conveying means for applying heat to the cans by conduction.

20 7. A cooker comprising a casing, track rails extending therein and adapted to sup-

port a line of cans, heating pipes in contact with said track rails, and conveyer means located alongside the track rails and having can engaging portions for moving the cans 25 along the track rails.

8. A cooker comprising a casing, can conveying means therein, heating pipes within the casing extending in heat conducting relation with the cans on the conveying means, 30 to apply heat to the can by direct conduction, and other heating pipes within the casing to supply heat to the cans by radiation and convection.

In testimony whereof I have hereunto set 35 my hand, at Los Angeles, California, this 16th day of December 1914.

WILLIAM J. SCHAEFER.
